(57) CLAIM

The ornamental design for a bathroom cabinet, as shown and described.

DESCRIPTION

FIG. 1 is a perspective view of a bathroom cabinet showing my new design;

FIG. 2 is a front elevational view thereof;

FIG. 3 is a right side elevational view thereof, the left side elevational view being a mirror image thereof; and,

FIG. 4 is a top plan view thereof.

The views of the bathroom cabinet that are not shown form no part of the claimed design.
